UNITED STATES PATENT OFFICE.

THOMAS H. SYMINGTON, OF ROCHESTER, NEW YORK.

UNDERFRAME-REINFORCE.

1,192,582.

Specification of Letters Patent. Patented July 25, 1916.

Application filed November 30, 1914. Serial No. 874,621.

To all whom it may concern:

Be it known that I, THOMAS H. SYMINGTON, a citizen of the United States of America, residing in the city of Rochester, county of Monroe, State of New York, have invented certain new and useful Improvements in Underframe-Reinforce, of which the following is a specification.

In view of the recently adopted regulations of the Master Car Builders' Association requiring that within a short time all wooden frame cars shall be provided with draft timbers extending back of the bolster, the production of an economical and efficient system of metal reinforcement for such cars whereby they are brought within the terms of these requirements or taken out of the class of wooden underframes and so braced and supported that the capacity to resist the stresses to which they are subjected under modern conditions of freight traffic is imparted to them has become an objective of great importance to the designers of freight cars, and such is the purpose of this invention. To this end I provide, in the present instance, in place of the wooden center sills which extend from end to end of the car, two metal channels or substitute sills of the same length as the wooden sills, the original sills being removed and replaced by the metal channels. In connection with these, in the preferred form of my invention I use thin wooden strips to which the floor boards of the car are fastened and which, in turn, are supported and given the required degree of rigidity by the channels. The metal channels, or substitute sills, which have their webs vertical and the edge flanges as shown turned outward, extend over and rest on the bolsters being reinforced at this point preferably by short sections of channel iron or the like, riveted to the substitute sills. At the ends I provide draft sills shown in the form of short sections of channel bar, depending from the substitute sills and having their webs vertical, the web of each channel being preferably in the plane of the web of the corresponding sill. The top flange of each draft sill member is secured to the bottom flange of the long channels or substitute sills. As thus arranged, the substitute construction at the ends presents two vertical, longitudinal surfaces placed apart preferably by a distance slightly greater

than that which separated the old wooden sills and to these the cheek plates are secured.

In the preferred form of the invention, the original cheek plates are preferably utilized. As these have lugs to engage the wooden sills, seating members in accordance with my co-pending application, Serial No. 871,278, are provided. In the present instance, the structure may be strengthened by having these seating members extend upward above the cheek plates so that they may be secured to the upper channels forming the substitute sills, as well as to the lower channels which in effect form the draft sills. While, in the preferred form of the invention, these extensions which are secured to the upper channels, are a portion of the seating member, they may be made integral with the cheek plates so that the cheek plates themselves are secured both to the upper channels or center sills and to the lower channels or draft sills.

In order that the invention may be fully understood, it is illustrated in the preferred form in the accompanying drawings, in which,

Figure 1 is a top plan of the back bone of the car, built up as described, the plan being broken away at one side at one end to illustrate one cheek plate in section; Fig. 2 is a section taken intermediately of the car as at 2, 2 of Fig. 1; Fig. 3 is a section on the line 3, 3 of Fig. 1; Fig. 4 is a view, corresponding to Fig. 3, of a slightly modified form of the invention; Fig. 5 is a view in elevation taken from a point between the center sills looking outward, showing one sill and the correlated parts in elevation; and Fig. 6 is a section on the line 6, 6 of Fig. 5.

Referring to the drawings by numerals, the device as illustrated consists of substitute sills 1 in the form of metal channels, extending from end to end of the car, wooden sill strips 2 secured to the top flanges 3 of the channels 1 and having the floor boards of the car in turn secured to them, and draft sills 4 in the form of metal channels having their top flanges 5 secured to the bottom flanges 6 of the channels 1, the vertical inner faces 7 of both channels being in the same plane which is also the plane of the inner face of the strip 2. The substitute sills 1 bear at their ends against

the end sills 15 at which point angle 16 may be secured to the sills providing a flange to engage the timber. The sills also rest on and cross the bolsters 8 at which point they 5 are reinforced by any suitable means as short channel sections 9 secured to the backs or inner faces 7 of the channels 1. The draft sills 4, referred to as having their top flanges secured to the bottom flanges of 10 the channels 1 are placed at each end of the substitute sills and tied together at the rear by plates 14 connecting the bottom flanges. To the inner faces of these channels, the 15 cheek plates 10 are secured. These may be of any type but preferably the original cheek plates taken from the wooden sills are used. To provide a suitable seating surface for 20 these, I preferably use seating members 11 such as are described in my co-pending application, but in the present instance, these may be extended upward above the cheek plates and above the draft sills having their upper extremities 12 secured to the substitute sills 1 or, as shown in Fig. 4, a new 25 type of cheek plate may be used having tongues or flanges 13 secured to the sills while the body of the cheek plate proper is secured to the draft sills or channels 4.

It will be apparent that by use of the 30 structure described, which constitutes the back bone of the car, replacing the wooden sills which have been found wholly insufficient to withstand the usage to which they are subject under present conditions, the de- 35 fects incident to wooden underframes, such as the breaking down of the sills across the bolster, pulling out of the fastenings which hold the cheek plates, and the like, are wholly eliminated. The substitute sills are 40 reinforced at the bolster and the cheek plates are provided with an amply sufficient sup- 45 port in the form of a depending channel secured to the bottom flange of the substitute sill. At the same time, the cheek plates themselves, or the seating members which hold them, are not only secured to the bot- 50 tom channel or draft beam, but may be pro- vided with additional means engaging the substitute sills whereby the cheek plates are secured to both members giving them an un- equalled rigidity.

Having thus described my invention, what I desire to secure by Letters Patent is:

1. In a wooden underframe car, substitute sills in the form of metal channels extending 55 from end to end of the car the web of the channel being vertical, wooden sill strips se- cured to the top flange of each channel, draft sills in the form of channels having their webs each in the plane of the web of 60 the corresponding substitute sill, a flange of each draft beam being secured to the corresponding flange of the substitute sill pro- viding a flat, vertically disposed seating 65 surface for the cheek plates, cheek plates se- cured to the draft sills, and seating means for the cheek plates, the said seating means overlying the draft beams and extending up- 70 ward into contact with the vertical face of the substitute sill, and means securing said means to both of said sills.

2. In an underframe for cars, longitudinal channels forming center sills, draft sills in the form of short channel sections secured to the center sills at the ends, both sets of 75 channels being placed with their webs vertical and in alinement, and the flanges con- 80 tacting and secured to each other, and cheek plates secured to the draft sills, the same having supporting means secured to both 85 the draft and the center sills.

3. In an underframe for cars, longitudinal channels forming center sills, draft sills in the form of short channel sections secured to the center sills at the ends, both channels 85 being placed with their webs vertical and in alinement, and their flanges contacting and secured to each other, and cheek plates secured to the draft sills, the same having 90 supporting means secured to both the draft and the center sills, the center sills extending the full length of the car and having reinforcing means in the form of short chan- 95 nel sections secured thereto over the bolster.

Signed by me at city of Rochester, State 95 of New York, this 27th day of November, 1914:

THOMAS H. SYMINGTON.
